UNITED STATES PATENT OFFICE.

EDWIN RUUD, OF PITTSBURG, PENNSYLVANIA, ASSIGNOR TO THE FUEL GAS AND MANUFACTURING COMPANY, OF SAME PLACE.

FLUID-METER.

SPECIFICATION forming part of Letters Patent No. 451,882, dated May 5, 1891.

Application filed August 20, 1890. Serial No. 362,518. (No model.)

To all whom it may concern.

Be it known that I, EDWIN RUUD, a citizen of the United States, residing at Pittsburg, in the county of Allegheny and State of Pennsylvania, have invented or discovered a certain new and useful Improvement in Fluid-Meters, of which improvement the following is a specification.

The object of my invention is to provide a double-acting fluid-meter in which, under a simple and compact disposition of parts, continuous delivery of fluid may be effected by balanced pistons or measuring-cups having a rectilineal traverse and actuating valve, and registering mechanisms through intermediate connections which are free from structural complication and adapted to be operated with a comparatively low degree of friction.

To this end my invention, generally stated, consists in the combination of a chambered casing, a series of pistons or measuring-cups each fitted to reciprocate in one of the chambers thereof, supply and exhaust passages leading into each chamber on opposite sides of its measuring-cup, and a vibratory transmitter coupled below the sealing-fluid level to each measuring-cup and to a shaft operating the valve and registering mechanisms.

The improvement claimed is hereinafter fully set forth.

In the accompanying drawings, Figure 1 is a vertical section through a meter embodying my invention at the line $x-x$ of Fig. 2; Fig. 2, a plan or top view with the cap removed; Fig. 3, a horizontal section at the line $y-y$ of Fig. 1; Fig. 4, a side view, in elevation, of the transmitter; and Fig. 5, a plan or top view of the same.

In the practice of my invention I provide a casing which is preferably of cast metal and is composed of a lower section 1 and an upper section 1^a , connected by bolts passing through flanges on the abutting faces of the sections. A series of measuring-chambers 5 is formed upon the upper section 1^a , said chambers being closed at top and open at bottom and projecting downwardly into the lower section 1. A valve-chamber 4 is secured upon the top of the upper section and an inlet or supply-nozzle 6, adapted to be connected to a fluid-supply pipe, leads into one

side of the valve-chamber. A valve-face 10 is formed upon the top of each of the measuring-chambers, from each of which faces a fluid receiving and delivery passage 11 leads into the top of the subjacent measuring-chamber. A similar passage 12 leads from each valve-face to and downwardly along the casing to the bottom thereof, and thence extends upwardly in the adjacent measuring-chamber 5 for a sufficient height to enable its open upper end to be cleared by a piston or measuring-cup 13, which is fitted to reciprocate in said chamber when the measuring-cup is at the lower limit of its traverse. An exhaust-port 9, located in each valve-face between the openings of the passages 11 and 12, opens into an exhaust-passage 8, extending around the inside of the casing-section 1^a , above the measuring-cups, said passage 70 communicating with a lateral outlet-nozzle or delivery-passage 7, adapted to be connected to a fluid-delivery pipe.

The measuring-cups 13, one of which reciprocates in each measuring-chamber 5, are light metallic shells, closed at their upper and open at their lower ends, and are of corresponding form to, but of slightly less dimensions in transverse section than, the measuring-chambers 5, so as to work freely therein, their true rectilineal movement being insured by vertical guide-rods 14, held at their ends in the tops of the measuring-chambers and in the bottom of the casing and fitting lateral recesses in the measuring-cups.

The upward and downward movements of the measuring-cups are effected by the pressure of the fluid admitted on their upper and lower sides through the passages 11 and 12, respectively, and their traverse is made coincident and equal in range by coupling them below the level of the sealing-fluid a in the measuring-chambers and central space of the casing to a transmitter 19, which is mounted on and adapted to vibrate about the center of a spherical bearing 20, fixed upon the bottom of the lower casing-section 1. The transmitter consists of a central hub, which is suitably recessed to fit freely over and move upon the bearing 20, and a series of radial arms corresponding in number with the measuring-cups, each of the arms being coupled

at its outer end to one of the measuring-cups by a connecting-rod 23, which is attached by a ball-joint 24, or equivalent swiveling connection to the top of the measuring-cup. The 5 lower end of each connecting-rod 23 is pivoted by a pin 23^a to a block 19^b, having a stem 19^c, which is journaled in the arm of the transmitter with its axis at right angles to that of the pin 23^a. This method of connecting the 10 lower ends of the connecting-rods to the transmitter, and the universal-joint connection of their upper ends to the measuring-cups, provides for all variations of relative position involved by the peculiar movement 15 of the transmitter effected by those of the measuring-cups, the movement of the transmitter being similar to that of the piston of a disk-engine, its arms vibrating upwardly and downwardly, and a central stem 19^a, with 20 which it is provided, traversing in a conical path.

An equalizing-chamber 28^a is fixed in each measuring-chamber, with its top adjacent to the level of the sealing-fluid, the equalizing- 25 chambers being preferably supported by the passages 12, to the upper portions of which they are secured, and being, as in prior constructions, provided for the purpose of reducing the error due to the depression and 30 elevation, respectively, of the sealing-fluid on the inside and outside of the measuring-cups.

The admission and exhaust of the fluid to be measured to and from the upper and lower sides of the pistons or measuring-cups 13 are 35 effected by slide-valves 30 of the recessed or D type employed in steam-engines, said valves being reciprocated on the valve-faces 10 and controlling the ports 11, 9, and 12 thereof. Movement is imparted to the valves 40 30 by a valve-shaft 31, journaled on bearings 32 in the casing and carrying on its lower end a crank 31^a, which is coupled to the upper end of the stem 19^a of the transmitter. A crank 34 is fixed upon the upper end of the valve- 45 shaft 31, and the valves 30 are coupled by connecting-rods 35 to the pin 36 of said crank, the valves being set to traverse at angles one to the other in proper correspondence with the traverse of the measuring-cups.

50 In order to increase or decrease the degree of traverse of the measuring-cups as may from time to time be required, I provide for the longitudinal adjustment of the valve-shaft 31 relatively to the transmitter, so as to vary 55 the range of circular movement of the connection of the central stem of the transmitter with the valve-shaft, and thereby to correspondingly vary the range of vertical vibratory movement of its arms. To this end an 60 adjusting-sleeve 31^b, having an internal thread at and near one of its ends, which engages a corresponding thread on the valve- 65 stem, is fitted around the latter between the bearings 32, against which it bears through interposed end washers 31^c. The adjusting-sleeve rotates with the valve-shaft, and by being turned thereon in either direction to

the proper degree and thereafter fixed in position by a set-screw effects the longitudinal adjustment of the valve-shaft which may be 70 required.

The registration of the measurement of fluid passing through the meter is effected by a registering mechanism of any suitable and known construction, which does not in and of 75 itself form part of my present invention, the same being located in a register-case 37, fixed upon the top of the valve-chamber and having a main shaft 39 journaled in bearings concentric with the valve-shaft and coupled 80 thereto, so as to rotate coincidently therewith, each revolution of the valve-shaft due to the upward and downward traverse of the measuring-cups effecting a revolution of the register-shaft and correspondingly actuating the 85 connected registering mechanism in the usual manner.

In the operation of the meter the fluid to be measured enters the valve-chamber through the inlet-nozzle 6 and passes into one or more 90 of the measuring-chambers above the measuring cup or cups thereof through the passage or passages 11 and into one or more of the chambers below the measuring cup or cups thereof through the passage or passages 12. 95 The pressure of the entering fluid forces the measuring-cups up and down, respectively, accordingly as it is exerted below and above them, their movements being, as before explained, made coincident, and one at least 100 being always effective in maintaining continuous rotation of the valve-shaft and operation of the valves by reason of their connection to the transmitter 19. In the upward movement of each measuring-cup the fluid 105 which has effected its previous downward movement is discharged through the passage 11, the exhaust-cavity of the valve 30, and the port 9 into the exhaust-passage 8, and thence to and through the outlet-nozzle 7. Similarly 110 in the downward movement of each measuring-cup the fluid which has effected its previous upward movement is discharged to the exhaust-passage and outlet-nozzle through the passage 12, the exhaust-cavity of the valve, 115 and the port 9.

I claim as my invention and desire to secure by Letters Patent—

1. In a fluid-meter, the combination of a lower casing-section, an upper casing-section 120 secured thereto and having a series of separate open-bottomed measuring-chambers projecting into the lower casing-section, a valve-chamber fixed upon the upper casing-section and communicating with an inlet-nozzle, pistons or measuring-cups fitted to reciprocate in the measuring-chambers, a vibratory transmitter mounted centrally between the measuring-cups and below the fluid-seal level, 125 connections coupling the measuring-cups to said transmitter, a valve-actuating shaft having a crank coupled centrally to the transmitter, fluid receiving and delivery passages 130 leading from the valve-chamber into each of

the measuring-chambers above and below its measuring-cup, an exhaust-passage having ports communicating with the valve-chamber, valves controlling the fluid receiving and delivery passages and exhaust-ports, and connections coupling the valves to the valve-actuating shaft, substantially as set forth.

2. In a fluid-meter, the combination of a chambered casing, pistons or measuring-cups fitted to reciprocate in the chambers thereof, a vibratory transmitter mounted centrally between the measuring-cups and below the fluid-seal level, connections coupling the measur-

ing-cups to the transmitter, a valve-actuating shaft having a crank coupled centrally to the transmitter, and an adjusting-sleeve engaging a thread on the valve-actuating shaft and abutting against fixed bearings to effect longitudinal adjustment of the shaft relatively to the transmitter, substantially as set forth.

5 In testimony whereof I have hereunto set my hand.

EDWIN RUUD.
